CLAIM

The ornamental design for a spoiler, as shown and described.

DESCRIPTION

FIG. 1 is a rear perspective view of a spoiler constructed in accordance with the teachings of the present invention shown operatively attached to a portion of a motor vehicle, it being understood that the broken line showing of the portion of the motor vehicle is for illustration only and forms no part of the subject invention.

FIG. 2 is an enlarged front view thereof;

FIG. 3 is an enlarged rear view thereof;

FIG. 4 is an enlarged right side view thereof;

FIG. 5 is an enlarged left side view thereof;

FIG. 6 is an enlarged top view thereof; and,

FIG. 7 is an enlarged bottom view thereof.
